WASHING MACHINE

Archie O. Long, Kansas City, Mo.

Application March 2, 1938, Serial No. 193,459

4 Claims. (Cl. 68—12)

This invention relates to washing machines, particularly to those of the rotary cylinder type, and has for its principal object to provide a machine of this character which is constructed to operate efficiently using smaller volumes of wash liquid than are usually required in this type of machine.

It is also an important object of the present invention to provide a washing machine of the rotary cylinder type wherein the cylinder is bodily movable to facilitate intake and discharge of the wash liquid and dumping of the washed clothes.

Other important objects of the invention are to provide a rotary cylinder machine which is of simple, inexpensive construction; to provide a more efficient movement of the wash liquid into contact with the clothes; to provide a simple speed reduction mechanism wherein the rotating power is applied directly to the cylinder; and to provide a washing machine of this character which is adapted for the washing of individual batches of clothes, each of the batches being washed and rinsed with fresh liquids separate from the other batches.

It is also a further object of the invention to provide a washing machine of this character equipped for substantially automatic operation.

In accomplishing these and other objects of the invention, as hereinafter pointed out, I have provided improved details of structure, the preferred forms of which are illustrative in the accompanying drawings, wherein:

Fig. 1 is a perspective view of a washing machine constructed in accordance with the present invention and showing the cylinder in washing position.

Fig. 2 is a schematic diagram of the electrical controls and the wiring therefor.

Fig. 3 is a side elevational view of the machine.

Fig. 4 is an end view of the machine.

Fig. 5 is a longitudinal section through the machine showing the cylinder moved to position for charging with a washing solution or rinse liquid.

Fig. 6 is a detail perspective view of the clothes charging end of the cylinder showing the cover plate removed therefrom.

Fig. 7 is a plan view of the machine.

Fig. 8 is a cross-section on the line 8—8 of Fig. 7.

Fig. 9 is a perspective view of a modified form of the invention.

Fig. 10 is an end elevational view of the closed charging end of the machine illustrated in Fig. 9.

a part of the end wall being broken away to show the interior construction of the washing cylinder.

Fig. 11 is a longitudinal section of the machine illustrated in Fig. 10.

Fig. 12 is a detail side elevation of the machine particularly illustrating the dumping lever and operating mechanism for retaining the cylinder in its three selective positions.

Referring more in detail to the drawings:

1 designates a washing machine constructed in accordance with the present invention and includes essentially a supporting frame 2, a rocker frame 3, and a rotating cylinder 4.

The supporting frame 2 includes substantially A-shaped side members 5 and 6 having their base portions 7 and 8 connected by a cross member 9. Formed at the apex of the side members are bearings 10 and 11 for journally mounting trunnions 12 and 13 of the rocker frame 4.

The rocker frame 3 is shown as including side arms 14 and 15 extending in parallel relation with the side members of the supporting frame and having inwardly directed ends 16—17 and 18—19 carrying semicircular, yoke-shaped arms 20—21 and 22—23 terminating in abutting ears 24 and 25, the ears 24 and 25 being secured together by fastening devices 26 so that the yoke-shaped arms form circular bands 21 having races 28 with their axis extending at right angles to the

axis of the bearings 10 and 11. The rocker frame also includes an arcuate bracket 29 that connects the side arms 14 and 15 at points preferably in alignment with the trunnions 12 and 13.

The cylinder 4 includes an annular wall 30, having frusto-conical ends 31 and 32 forming axial openings 33 and 34. Fixed to the ends 31 and 32 in encircling relation with the openings 33 and 34 are frames or collars 35 and 36 encircled by the yoke-shaped arms of the rocker

frame and having bearing races 37 cooperating with the bearing races 28 to mount sets of anti-friction bearing members, such as rollers 39 and 40, as best shown in Fig. 5. The bearing races 37 are inset into the collars 35 and 36 to form

annular stop shoulders 41—42 and 43—44 to engage the respective side faces of the yoke-like arms of the rocker frame 3.

The washing solutions and rinse liquids are charged and discharged from the cylinder through the opening 33 and this opening is normally covered by a disk-like closure 45 having an angularly extending peripheral flange 46, conforming in shape to the end 31 for providing a valve face 47 adapted to sealingly engage the inner face 48 of the cylinder that encircles the

opening. The closure is normally retained in seated position by a coil spring 49, having one end abutting against an axial boss 50 projecting from the inner face of the closure and its opposite end against a bar 51 extending transversely across the cylinder, the ends of the spring 49 being retained in concentric alignment with the axis of the cylinder by cylindrical lugs 52 and 53 projecting from the boss 50 and bar 51, as shown in Fig. 5. The closure is guidingly retained for movement to and from open position by means of pins 54 that are fixed to and project outwardly from the outer face of the closure and are guidingly mounted in openings 55 that are formed in inwardly extending lugs 56 on the collar 35.

The collar 36 which encircles the opening 34 has an internal, annular shoulder 57 for seating the rim 58 of a cover plate 59, the cover plate 59 being preferably provided with transparent panels 60 and 61 on opposite sides of a central cross bar 62. The cover plate is removably retained on the annular shoulder by a cross bar 63 that is threadedly supported on a screw shaft 64. The screw shaft 64 has its inner end provided with a head 65 that is rotatably retained in a socket 66 on the cross member 62 of the cover plate, as shown in Fig. 5. The outer end of the screw shaft is provided with a hand wheel 67 whereby the shaft may be rotated. The outer ends 68 and 69 of the cross bar engage under arcuate lugs 70 and 71 that project inwardly from the inner face of the collar 36, as best shown in Fig. 6. When the cover plate is applied the cross bar 63 is inserted so that the ends thereof pass between the adjacent lugs 70 and 71 whereupon the bar is swung arcuately so that the ends 68 and 69 thereof engage under one of the pairs of lugs. The hand wheel is then rotated to move the ends of the cross bar into rigid engagement with the arcuate lugs and the cover plate against its seat.

The cylinder is thus mounted for rotation on an axis extending transversely and intersecting the axis of the trunnions on which the rocker frame is adapted to oscillate so that when the articles to be washed are placed therein they are carried by the cylinder up the side thereof until the forces of gravity overcome the rotational forces tending to carry the articles with the cylinder whereupon the articles drop back into the main body of the wash liquid in the bottom of the cylinder. In order to assure movement of the articles being washed incidental to rotation of the cylinder, and to assure picking up of the water by the cylinder wall, I provide the cylinder with an inner cylindrical liner 72 that is spaced inwardly from the outer wall to provide a liquid retaining space 73. The liner 72 is fixed directly to the cylinder and has a plurality of perforations 74 of sufficient size so that when the liquid collects in the space 73 at the lower diametrical side of the cylinder, it is carried in the space 73 as the cylinder rotates and is emptied through the perforations 74 above the axis of the cylinder, and whereby the liquid flushes the clothes as they are being rolled about within the cylinder.

In assisting the cylinder to carry the clothes therewith so that they will roll over and drop back into the wash liquid that normally remains in the bottom of the cylinder, the cylinder is provided with a plurality of inwardly extending blades or vanes 75 which are shown as being

formed of material bent to form hollow vanes of V-shaped cross-section and provided with perforations covering the areas extending from the liner to the inner edges thereof, as shown in Fig. 8. The vanes thus form liquid retaining pockets for carrying the wash liquid incidental to rotation of the cylinder. The sides of the vanes are attached to the liner and spacers 78 are inserted in the annular space between the cylinder liner and the outer wall of the cylinder, as best shown in Fig. 8.

The vanes preferably extend from the end 32 toward the opposite end of the cylinder where they connect with a perforated, ring-like shield 79 corresponding in shape to the end wall 31 of the cylinder. The closure 45, including its spring and supporting cross bar, are preferably covered by a perforated, substantially concavo-convex partition 80 arranged with the concave side outermost. The inner periphery of the shield 79 joins with the partition 80 to form an annular drainage space 81 into which the wash liquids drain to the exclusion of the articles being washed, when the cylinder is tipped incidental to discharging the wash liquid, as later described.

In order to rotate the cylinder about its longitudinal axis the wall thereof is provided at one side of the arch-shaped bracket 29 with a band 82 having grooves 83 for receiving belts 84. Mounted on the arch-shaped bracket 29 is a motor 85 provided with a gear head having its driven shaft 86 provided with a pulley 87 having grooves 88 aligning with the grooves 83 and in which the belts 84 operate. The pulley 87 is small in diameter relative to the diameter of the cylinder so that the cylinder is driven at the proper speed without further reduction. The direct belt drive therefore simplifies the drive and eliminates necessity of expansive speed reducing mechanisms as is necessary in conventional cylinder machines. The motor 85 is preferably of the reversing type and is energized through an automatically actuated reversing switch 89, later described, so that when washing, the cylinder is rotated first in one direction and then in the other to assure maximum agitation of the clothes in the washing solution.

In order to facilitate charging of the cylinder with wash liquid and to render the machine substantially automatic, the cylinder is oscillated on the trunnions 12 and 13 so that the inlet opening 33 thereof is raised into charging relation with a tank 90 which contains the washing solutions, the tank 90 being supported above the cylinder as shown in Figs. 1 and 5 on a post or other support 91. The tank 90 has a discharge opening 92 in the bottom thereof which is connected with a shut-off solenoid operated valve 93 carrying a flexible tube 94 that is adapted to enter within the open end of the cylinder when the cylinder is oscillated to the position shown in Fig. 5. The tank is also equipped with a sight gauge 95 having graduations to indicate volume of water required per pound of clothes.

To provide for automatic opening of the closure 45, when the cylinder is tipped to the position shown, I provide the bearings 10 and 11 with the cams 96 and 97 having high lobe portions 98 and 99 projecting horizontally in the direction of the liquid charging end of the cylinder. Reciprocably mounted in suitable guides 100 and 101 on the rocker frame are push rods 102 and 103. Carried on the rear ends of the push rods are rollers 104 and 105 for following the contour of the cams

as the cylinder is tipped on the trunnions. The opposite ends of the push rods carry yoke-shaped arms 106 and 107 having their inner ends 108 and 109 terminating within the open end of the cylinder and carrying rollers 110 and 111 rollingly engaging the outer face of the closure 45, as best shown in Fig. 1. The arms are supported in functional position against the rotational thrusts of the closure by means of pins 112 and 113 that project from the arms 106 and 107 and are guidingly supported in openings 114 and 115 in the ends of the rocker frame as best shown in Figs. 1 and 7. The push rods are normally urged to closure opening position and the rollers thereon against the cams by means of coil springs 116 and 117 that are sleeved on the rods and have one end bearing against the guides 100 and their opposite ends against adjusting collars 118 whereby the rods are adjusted for length in taking up play between the cams and the closure plate 45. When the cylinder is in horizontal or operative position, shown in Fig. 1, the rollers 104 and 105 are on the high lobe portions of the cams so that the closure plate engaging portions are in retracted position and the coil springs 116 and 117 in compressed condition. Therefore if the cylinder rocks upwardly the rollers 104 and 105 ride into the dwells of the cams allowing the springs 116 and 117 to come into play to cause the rollers to press inwardly on the closure 45 against action of its spring 49 so as to move the closure plate 45 from seating position as shown in Fig. 5. The closure plate is similarly opened when the cylinder is rocked to the dotted line position as shown in Fig. 5, since the cams are symmetrical on opposite diametrical sides of the high lobe portions thereof.

In order to oscillate the cylinder to and from charging and discharging positions, the rocker frame is provided with a gear segment 119 that is fixed to the side bar 14 and is meshed with a pinion 120 on the armature shaft of a motor 121, the motor 121 being mounted on the side frame 5 as shown in Fig. 1. The motor 121 is also of the reversible type and is automatically operated in timed relation with the motor 85, as now to be described.

The motor circuits are illustrated in diagram in Fig. 2 and are supplied with an energizing current from service lines 122 and 123 through branch conductors 124—125 and 126—127, the conductors 124 and 127 being directly connected with the respective motors but the conductors 126 and 125 connect with reversing switches 89 and 129 to selectively connect the field windings of the respective motors into the circuit through conductors 130—131 for the motor 85 and 132—133 for the motor 121. Also interposed in the conductor 126 leading to the motor 85 is a switch 134 adapted for manual operation to close the circuit and which is adapted to be opened automatically by a solenoid 135 in a timing circuit including conductors 136 and 137 which connect with a timing switch 138. The timing switch 138 includes a contact arm 139 that is moved across a series of contacts 140, 140', 141, 142 and 143, which vary in length and spacing corresponding to the dwell in operating sequences of the washing cylinder. The arm 139 is rotated by a motor 144, having its terminals connected by conductors 145 and 146 with the service lines 122 and 123. Interposed in the conductor 146 is a manually closed switch 147 and which is adapted to be opened automatically by a solenoid

148 having connection with the contact 143 through a conductor 149 and by a conductor 150 with the secondary winding 151 of a transformer 152, the primary 153 of which is connected with the service lines 122 and 123. The other terminal of the secondary winding is connected by a conductor 154 directly with the switch arm 139. The contacts 140, 141 and 142 respectively are connected by conductors 155, 156 and 157 with solenoid switches 158, 159 and 160 that are connected in the motor circuit 121, the fixed contacts of the switches being connected by a common conductor 161 with the service line 123. The solenoid actuated contacts of the switches 159 and 160 are connected with the conductor 132 while the corresponding contact of the switch 158 is connected with the conductor 133. The switches 158 and 159 are supported on the side frame 5 in position to be engaged by lugs 162 and 163 that are mounted on the opposite ends of the gear segments. The solenoid switch 160 is mounted on the side frame at a point intermediate the switches and is adapted to be engaged by the lug 163. One terminal of the solenoid valve 93 is connected by a conductor 93' with the contact 140' and the other terminal, as well as the other terminals of the solenoid switches 158, 159 and 160, are connected by a conductor 93'' with the conductor 150.

In order to actuate automatically the reversing switch 128 I provide a spring 164 for normally holding the switch arm in circuit closing position relative to the conductor 130 and the switch is moved to circuit closing relation with the conductor 131 by a solenoid 165 having its leads connected with the secondary of a transformer 166 through conductors 167 and 168. The primary winding 169 is connected to the service wires 122 and 123. Interposed in the circuit of the secondary winding is a timing element 170 for alternately opening and closing the solenoid circuit so that the arm 128 of the switch 89 is alternately moved from one contact to the other, thereby reversing direction of rotation of the armature shaft of the motor which reverses rotation of the cylinder.

To prevent building up of pressure, when the washing machine is filled with hot washing liquid, I provide the cylinder with a relief valve 171, having an operating arm 172 that is engaged by a cam 173 upon each revolution of the cylinder.

In operating a washing machine constructed and assembled as described, the switch 129 is moved to close circuit between the conductors 125 and 132 to energize the motor 121 so that the cylinder rocks to the dotted line position in Fig. 5. When the cylinder is in convenient position to insert the clothes the switch 129 may be opened to stop operation of the motor 121. The cover plate 59 is then removed and the clothes to be washed inserted through the opening 34. After the clothes have been inserted the cover plate is reapplied and secured tightly in position. The normal or starting position of the switch arm 139 is between the contacts 143 and 140. The switches 134 and 147 are then closed to energize the motor 85 to rotate the cylinder and the motor 144 which actuates the timing switch. As soon as the arm 139 engages the contact 140, circuit is established from the secondary winding 151 through the conductor 154, arm 139, contact 140, conductor 155, solenoid switch 158 and back to the secondary of the transformer, thereby en-

ergizing the solenoid 158 and closing circuit to the motor 121 in the opposite direction through the conductors 161 and 133. This causes reverse operation of the motor 121 to swing the end of the cylinder having the opening 33 into receiving relation with the hose 94. When the cylinder has reached the limit of its travel the lug 162 engages the switch 158 to open the circuit, thereby stopping the motor 121. During upward tilting movement the closure plate 45 has moved from open through closed and again to open position since the rollers 104 and 105 have moved across the high lobe portions of the cams and by the time the cylinder has moved to its upper position the rollers are in the low dwells of the cams so that the springs are effective in opening the closure member. The switch arm 139 then engages the contact 140' to effect opening of the valve 93 to discharge a given quantity of washing fluid into the cylinder, as indicated on the gauge 95. By the time the switch arm 139 moves off contact 140', the required amount of washing solution has been admitted and the valve is automatically closed. The switch arm 139 then engages the contact 141 so that the solenoid of the switch 159 is energized to close that switch so that the motor 121 is energized by a current flowing through the conductor 161, switch 159 and conductor 132 which effects rotation of the motor 121 in the opposite direction. As soon as the cylinder has been moved into substantially horizontal position the lug 163 engages the switch 159 to open the switch and interrupt circuit to the motor 121. The cylinder is then retained in horizontal position, as shown in Fig. 3. In this position the rollers of the push rods rest on the high lobes of the cams so that the springs 116 and 117 are compressed and the spring 49 is again effective in seating the closure plate 45. The switch 134 having been closed to energize the motor 85, current flows through the conductors 126 and 130 to the motor 85 and back to the line through the conductor 127. The motor will operate to rotate the cylinder in one direction until the timing element is effective in closing circuit to the solenoid which opens the switch 89 against action of its spring and effects contact between the conductors 126 and 131 to reverse operation of the motor 85 which causes the cylinder to reverse its direction of rotation. The motor 85 thus continues to operate first in one direction and then in the other direction for the entire period that the arm 139 of the timing switch is moving between the contacts 141 and 142. During rotation of the cylinder the clothes tend to ride up the side wall of the liner under the lifting influence of the vanes until the force of gravity overcomes the lifting force, whereupon the clothes roll over and drop back into the bottom of the cylinder. Simultaneously the wash liquid is carried between the space between the liner and is caused to discharge over the clothes. Reverse rotation of the tub produces sufficient agitation to be thoroughly effective in washing the clothes. When the contact arm 139 reaches the contact 142, circuit is established through the solenoid of the switch 160 so that current flows to the motor 121 through the conductors 161 and 132 which again energizes the motor to continue tipping thereof in a counter-clockwise direction or into the dotted line position shown in Fig. 5. The push rod rollers move off the high lobes of the cams and the springs thereon again become effective to open the closure plate 45. The wash liquid is then discharged through the opening 33

aided by continued rotation of the cylinder. During this position of the cylinder the partition 80 and shield 79 keep the clothes from contact with the closure plate 45, so that the water may run freely through the perforations in the shield and partitions and be discharged into a sump that is formed in the floor on which the machine is supported. By the time the cylinder has been emptied of washing fluid, the switch arm engages the contact 143 which causes energization of the solenoids 135 and 148 to open automatically the switches 134 and 147, thereby stopping rotation of the cylinder and opening of the timing switch circuit. The washing machine cylinder will remain in this position until the operator again closes the switches 134 and 147. The operator will then remove the cover plate 59, after which he will close the switch 129 so that the cylinder is swung to clothes dumping position. The switch 134 may also be closed to start rotation of the cylinder, thereby aiding in discharge of the clothes through the opening 34 into an extractor or other receptacle arranged to receive them.

The form of the invention illustrated in Figs. 9 to 12 inclusive is adapted for use in small laundries. In this form of the invention the support includes a pair of substantially A-shaped frames 174 having bearings 175 for mounting a rock shaft 176. Fixed on the rock shaft is a transversely arranged bearing sleeve 176' for rotatably mounting the tubular spindle 177 that carries the washing cylinder 178. The washing cylinder 178 includes a substantially flat, disk-like rear wall 178' to which the spindle 177 is secured and an annular, peripheral wall 179 terminating in a frusto-conical front wall 180 which carries an annular frame 181 forming an opening 182 through which articles to be washed are inserted into the cylinder. The opening 182 is closed by a cover 183 secured in place by a clamping mechanism 184 similar to that illustrated in the preferred form of the invention.

The interior of the cylinder is provided with a perforated annular liner 185 that is spaced inwardly from the wall 179 and a perforated partition or guard 186 spaced from the rear wall 178'. The cylinder is also provided with perforated vanes 187, similar to the preferred form of the invention. The rear end of the tubular spindle 177 is normally closed by a valve-like door 188 that is hinged to the spindle, as at 189, and secured in closed position by a spring latch 190. The cylinder is driven by belts 191 that operate over a pulley ring 192 on the cylinder and over a pulley 193 on the armature shaft of a motor 194; the motor being supported on a post 195 projecting upwardly from the bearing sleeve 176'. In order to rock the cylinder to and from the respective servicing positions described in connection with the preferred form of the invention, the rock shaft is provided with a lever 196 that projects radially therefrom and carries a grip actuated pawl 197 that is adapted to engage selectively notches 198, 199, 200 and 201 in the periphery of a segment 202 that is carried on one of the side frames 174. By actuating the lever and allowing the pawl to engage one of the respective notches, the cylinder may be moved to and supported in washing solution charging and discharging positions and to positions for inserting the clothes and discharging the clothes through the opening 182. In this form of the invention the washing and rinsing solutions are contained in bottles or similar containers 204 that are car-

ried on a rotating shelf 205, located in convenient position relatively to the location of the washer. The necks 206 are turned down and adapted to align with a funnel 207 carrying a hose 208 that is adapted to be inserted into the tubular spindle 177 when the cylinder is moved to position for charging it with washing solution. The necks of the containers are closed by corks 209 and the tops are open for filling purposes. The operation of the invention illustrated in Figs. 9 to 12 inclusive is substantially that illustrated in the preferred form of the invention.

While I have described the operation of the machine illustrated in Fig. 1 as being used only with washing solutions, it is obvious that other tanks may be provided for containing rinses and other solutions that are used in the processing of clothes in laundry work.

From the foregoing it is obvious that I have provided a washing machine wherein the clothes may be washed with a minimum amount of washing solution as all of the solution is effective on the clothes. It is also obvious that the automatic operation facilitates handling of individual batches of washing and each batch may be segregated and washed in separate water from the other batches. Since the cylinder is sealed at both ends it may be entirely filled with rinse water to reduce the number of rinses ordinarily required, the idea being that rinsing is diluting and that by filling the cylinder full, less rinses are required.

What I claim and desire to secure by Letters Patent is:

1. In a machine of the character described, a washing cylinder having concentric axially arranged bearing rings forming a wash liquid inlet and discharge opening at one end of the cylinder and a clothes charging opening at the other end of the cylinder, closures for said openings, a frame having bearing members journaling the bearing rings for rotation of said cylinder about the axis thereof, means for rotating the cylinder, means for tilting supporting said frame about a transverse axis relatively to the cylinder axis for bodily moving the cylinder to raise and lower the wash liquid inlet and discharge end of the cylinder to and from charging and discharging positions, and automatic means for opening and closing the closure at said end of the cylinder responsive to bodily movement of the cylinder.

2. In a machine of the character described, a washing cylinder having axially arranged bearing

rings forming a wash liquid inlet and discharge opening at one end of the cylinder and a clothes charging opening at the other end of the cylinder, closures for said openings, a rocker frame having bearing members journaling the bearing rings, trunnions on the rocker frame having a common axis arranged transversely of the cylinder axis, a support for the trunnions, means for moving the rocker frame on the support about the axis of said trunnions to raise and lower the wash liquid inlet and discharge end of the cylinder to and from charging and discharging positions, and means for opening and closing the closure at said end of the cylinder responsive to movement of the rocker frame.

3. In a machine of the character described, a washing cylinder having axially arranged bearing rings forming a wash liquid inlet and discharge opening at one end of the cylinder and a clothes discharging opening at the other end of the cylinder, closures for said openings, a rocker frame having bearing members journaling the bearing rings, trunnions on the rocker frame having a common axis arranged transversely of the cylinder axis, a support for the trunnions, means for moving the rocker frame about said transverse axis of the trunnions to raise and lower the wash liquid inlet and discharge end of the cylinder to and from charging and discharging positions, automatic means for opening and closing the closure at said liquid inlet end of the cylinder responsive to movement of the rocker frame, a motor support on the rocker frame, a motor on the motor support, a driving ring on the cylinder and a driving connection between the motor and the driving ring to rotate the cylinder.

4. In a washing machine, a cylinder having charging openings at opposite ends, a perforated liner spaced from the inner wall of the cylinder, means fixing the liner in the cylinder, closures for said openings, means oscillatably mounting the cylinder for tilting movement transversely to its axis in opposite directions to respectively bring said openings to charging positions, a guard covering one of said openings and cooperating with the liner for forming a drainage passageway to one of said openings when the cylinder is tilted in a direction to bring the other opening into charging position, and means mounting the cylinder for rotation about the axis of said cylinder.

ARCHIE O. LONG.
